[57] **ABSTRACT**

The alloys of this invention contain relatively small, but nonetheless significant, amounts of tungsten and molybdenum for solid solution strengthening, chromium for oxidation and sulfidation resistance, tantalum for solid solution and carbide strengthening, and aluminum and titanium to enhance the strength by precipitation of a fine dispersed phase, gamma prime $\text{Ni}_3(\text{Al},\text{Ti})$.

5 Claims, No Drawings

NICKEL BASE ALLOY

This invention relates to nickel base alloys exhibiting high strength, stability, ductility and resistance to corrosion, sulfidation and oxidation at elevated temperatures and which are useful for blades, vanes and integrally cast turbine wheels.

The alloys of this invention contain relatively small, but nonetheless significant, amounts of tungsten and molybdenum for solid solution strengthening, chromium for oxidation and sulfidation resistance, tantalum for solid solution and carbide strengthening, and aluminum and titanium to enhance the strength by precipitation of a fine dispersed phase, gamma prime $\text{Ni}_3(\text{Al},\text{Ti})$.

Co — 8.50–9.50
Mo — 1.85–2.05
W — 3.65–5.0
Ta — 4.5–8.0
5 Ti — 3.90–4.20
Al — 3.20–3.60
Ti + Al — 7.25–7.70
B — 0.010–0.020
Zr — 0.08–0.25
10 Ni — balance

Exemplary alloys in accordance with the teachings of this invention had the compositions shown in Table I which follows:

TABLE I

Heat No.	C	Cr	Co	Mo	W	Ta	Ti	Al	TiAl	B	Zr	Ni
I	.17	12.97	9.37	2.05	3.99	4.86	3.98	3.33	7.31	.014	.12	Balance
II	.17	12.97	9.37	2.05	3.99	5.86	3.98	3.33	7.31	.014	.12	Balance
III	.17	12.97	9.37	2.05	3.99	7.86	3.98	3.33	7.31	.014	.12	Balance
IV	.22	12.97	9.37	2.05	3.99	5.86	3.98	3.33	7.31	.014	.12	Balance
V	.22	12.97	9.37	2.05	3.99	7.86	3.98	3.33	7.31	.014	.12	Balance
VI	.20	12.31	9.18	1.94	3.72	6.70	4.08	3.38	7.46	.014	.15	Balance
VII	.17	12.97	9.37	2.05	5.00	4.86	3.98	3.33	7.31	.014	.15	Balance
VIII	.17	12.97	9.37	2.05	6.00	4.86	3.98	3.33	7.31	.014	.15	Balance

Compositions of the following analyses are contemplated as within the scope of the present invention, in weight percent, the balance being Ni except for incidental impurities:

C — 0.30 max.

Cr — 11–15

Co — 8–12

Mo — 1–2.5

W — 3–8

Ta — 4–10

Ti — 3.5–4.5

Al — 3–4

Ti + Al — 7–8

B — 0.005–0.025

After vacuum melting, the alloys noted above were vacuum cast into $\frac{1}{4}$ inch ASTM test bars (ASTM E8) 30 and subjected to stress rupture testing according to ASTM Standard E139. The test bars were heat treated before testing as follows: heated to 2,050°F, held at that temperature for 2 hours then air cooled, then reheated to 1,550°F and held at 1550°F for 4 hours, then air cooled, then reheated to 1,400°F and held at that temperature for 16 hours then air cooled.

After the heat treatment described above, stress rupture tests were conducted on cast test bars representative of each of the heats in the heat treated condition 40 at 1,400°F/95Ksi, 1,400°F/100Ksi, 1,700°F/39Ksi and 1,800°F/29Ksi. The results are given in Table II.

TABLE II

Heat No.	Stress Rupture Test Results (ASTM E139)							
	1400°F/95Ksi Life (hrs.)	E1 (%)	1400°F/100Ksi Life (Hrs.)	E1 (%)	1700°F/39Ksi Life (Hrs.)	E1 (%)	1800°F/29Ksi Life (Hrs.)	E1 (%)
I					85	10	68	7
II			190	5	181	5	80	5
IV			102	5	89	5	67	11
V			249	5	116	8	43	10
					130	6		
					140	7	74	5

Zr — 0.05–0.40

A more preferred range of compositions is as follows (in weight percent):

C — 0.10–0.22

Cr — 12.30–13.50

Corresponding values for two presently known commercial alloys are appended to Table II for comparison.

60 INCO 713C is reported to be an alloy with a nominal composition of

C	Cr	Mo	W	Cb	Ti	Al	Zr	B	Ni
0.14	13.0	4.5	0.20	2.0	0.75	5.75	0.05	0.012	Balance

MAR-M-421 is reported to be an alloy with a nominal composition of

elevated temperature and consisting essentially of the following in weight percent:

C	Cr	Co	Mo	W	Cb	Ti	Al	Zr	B	Ni
0.15	15.8	9.5	2.0	3.8	2.0	1.8	4.3	0.05	0.015	Balance

From the results in Table II, the superiority of the alloys of this invention will be readily seen.

We claim:

1. A nickel base alloy exhibiting high strength, ductility, sulfidation and oxidation resistance and stability at elevated temperature and consisting essentially of the following in weight percent:

C—0.30 max.

Cr—11-15.0

Co—8-12

Mo—1-2.5

W—3.65-8

Ta—4.5-10

Ti—3.5-4.5

Al—3-4

Ti + Al—7-8

B—0.005-0.025

Zr—0.05-0.40

Ni—balance

2. A nickel base alloy exhibiting high strength, ductility, sulfidation and oxidation resistance and stability at

10 C—0.10-0.22

Cr—12.30-13.50

Co—8.50-9.50

Mo—1.85-2.05

W—3.65-5.0

Ta—4.5-8.0

Ti—3.90-4.20

Al—3.20-3.60

Ti + Al—7.25-7.70

20 B—0.010-0.020

Zr—0.08-0.25

Ni—balance

25 3. A nickel base alloy according to claim 1 which has been heat treated to produce a desired morphology of carbides and gamma prime.

4. An article formed of the alloy of claim 1.

5. A vacuum cast article consisting of the alloy of claim 1.

UNITED STATES PATENT OFFICE
CERTIFICATE OF CORRECTION

Patent No. 3,793,011 Dated February 19, 1974
Inventor(s) Ranes P. Dalal et al.

It is certified that error appears in the above-identified patent and that said Letters Patent are hereby corrected as shown below:

Columns 1 and 2, Table II should appear as shown on the attached sheet.

Signed and sealed this 1st day of October 1974.
